UNITED STATES PATENT OFFICE.

JOHN ERICKSON, OF CHICAGO, ILLINOIS, ASSIGNOR, BY MESNE ASSIGNMENTS, TO AUTOMATIC ELECTRIC INC., OF CHICAGO, ILLINOIS, A CORPORATION OF DELAWARE.

SWITCHING MECHANISM.

Application filed September 11, 1925, Serial No. 55,689. Renewed June 6, 1928.

The present invention, broadly stated, relates to switching mechanisms used in automatic telephone systems. More particularly, my invention is concerned with improvements 5 applied to switches of the well known vertical and rotary type as disclosed in the U. S. patents to Keith, Erickson, and Erickson, Nos. 815,176 and 815,321, both granted March 13, 1906.

10 A brief account of the objects of my invention with reference to the mechanisms disclosed in the above patents shall first be given so that the detailed description which is to follow may be readily understood and fully 15 appreciated. In view of the fact that the apparatus is well known, it is thought to be unnecessary to go into minute detail of its functions. Accordingly, I shall limit myself to the description of operations only which are 20 necessary for the comprehension of my invention.

Referring now to the operation of the switching apparatus disclosed in the patents cited above, a shaft carrying a number of 25 wipers will first be raised in a vertical direction, positioning the wipers opposite a certain level or row of contacts. The shaft will then be rotated horizontally until the wipers are brought into engagement with a certain 30 set of contacts representing either an idle trunk or a called line. Considering particularly the rotary operations, it will be seen that a relatively great amount of friction caused by the wipers brushing over the contacts must be overcome by a magnet executing the step by step rotary movement. This 35 friction does not only result in unnecessary wear and tear of the various parts, such as the wipers, the bank contacts, and the pawl operated by the armature of the rotary magnet and forcing itself into the teeth of the 40 rotary ratchet cylinder on the switch shaft, but it also necessitates a powerful magnet and limits the speed of the operation to a definite point beyond which a safe and positive 45 action cannot be accomplished. In other words, the speed of the switch mechanism is largely depending on its mechanical construction.

50 It is, however, a well known fact that the period of time consumed by a switching mechanism in setting up a connection, is one of the vital factors in the operation of automatic telephone systems. Speed and mechanical 55 friction being in a relation of reciprocity, it

is evident that a reduction of friction must benefit the problem of speedier operation.

One of the objects of my invention is to reduce the friction between certain moving parts participating in the rotary motion of 60 the switch without impairing their positive functions. In a switch, such as I have chosen for illustrating my invention, having two line and one private wipers, I eliminate the friction of the two line wipers entirely and, 65 to some extent reduce also the friction of the private wiper. In other words, the line wipers are withdrawn from the bank contacts during the rotary movement, while the private wiper touches the private contacts just 70 sufficiently to warrant safe operation. After the wipers are advanced to a desired set of contacts in a level, they will be forced against the contacts and locked in operated position electrically or mechanically as will be seen 75 later on from the detailed explanation.

The results of this arrangement are obvious. Undue wear and tear of the parts brought into play during the rotary movement of a switch is eliminated, which will be 80 reflected in a prolonged service of the apparatus, obviating frequent readjustments and replacement of worn out parts. In other words, the life of a switch will be increased. Apart from this gain, which in itself is highly desirable, I am also enabled to utilize the power formerly used for subduing mechanical friction for increasing the speed of the 85 rotary operations. If increased speed is not desired for some reason or other, the advantages of my improvements may be realized in some other form which readily suggests itself, for example, by employing a weaker 90 rotary magnet as was formerly necessary for attaining the same results, thus reducing the initial cost of the switch and also operating 95 expenses. Although the saving might appear to be negligible if only one switch is considered, it will be perceived at once that a decided gain will result in complex systems using a great number of switches, in some instances running into thousands.

Another object of my invention has more particularly to do with the maintenance of the switching apparatus. Although this 105 problem is inherently affected by the improvements intimated in the foregoing paragraphs, it being evident that a mechanism subjected to but a minimum amount of wear will need only a minimum amount of care 110.

and supervision, I also employ an improved and simplified arrangement of bank contacts and simplified wipers, cheap in manufacture, reliable in operation and reducing the possibility of trouble caused by external forces, human and otherwise, to a minimum.

Referring to the arrangement of bank contacts, it will be remembered that in the usual switches the private contacts are located in a bank and arranged in rows, each row containing but single contacts, while the line contacts corresponding to the respective private rows are arranged in a separate bank, also in rows or levels, each level, however, containing double as many line contacts as there are private contacts and arranged in pairs. To elucidate this point in order to vividly recall the usual arrangement of the bank contacts, if ten lines were located in a certain level, the private row would contain the ten private contacts arranged in physical sequence, while the row in which the line contacts are located, would contain twenty contacts, each line or trunk being composed of two conductors. The two contacts comprising a line or trunk are in the usual arrangement, positioned opposite each other and separated by an insulator.

This arrangement, although it proved satisfactory through long established use, has a number of inherent faults. In the first place, the manufacture of the line bank is extremely expensive due to the fact that pairs of contacts must be arranged, insulated from one another and rigidly fixed in place in accordance with their corresponding contacts in the private bank which requires a more complicated process and more skill than the assembling of single contacts in sequence. Secondly, there is an inductive influence between the contacts, which, in effect, represents a capacitance bridged across the line or trunk and which can only be reduced to a permissible maximum by the use of heavy partitions made from high grade insulators. Thirdly, there is the problem of preventing accumulation of dust upon the contacts. The deteriorating effect produced is, however, less the amount of dust the contacts collect in the course of time, but more so its unequal distribution. The lower row of line contacts, protected by their location underneath the partition, will, in some instances be almost wholly dust free, while the upper row exposed as it is, is pre-eminently fitted to provide for ready dust collection. Thus, conditions not only contribute towards unequal wear of the wipers and contacts as the upper line wiper, during rotation, will scrape the dust and grind over the contacts, while the lower wiper will be less subjected to wear, but the contacts of the upper row will after some time be covered with a solid crust of dust particles, greatly affecting the efficiency of the apparatus. The numerous defects re-

sulting from those conditions may be temporarily remedied by readjusting the tension of the wipers, but it will be apparent that such readjustments, however skillfully applied, will only add to future troubles.

To overcome the objectionable features which I have picked at random and intimated above, I propose, in accordance with one of the objects of my invention, to arrange the line contacts in a similar manner as is done in case of the private contacts, viz, in a physical sequence and not in pairs. This, of course, necessitates a modification of the two line wipers. It will be seen presently, that I have modified and simplified the line as well as the private wipers. By way of preliminary explanation, I may state that the wipers advance underneath the contacts in a certain row, the line wipers not touching the contacts, while the private wiper advances with a slight pressure. The line wipers will be forced against and into firm engagement with the line contacts and the tension of the private wiper will be increased after all wipers have been positioned opposite the proper set. In releasing, the line wipers will first be withdrawn from the contacts, and the tension of the private wiper will be lowered to its original value before starting on the return movement to normal position.

Still another object of my invention resides in a novel operating magnet, i. e., a magnet used for operating the shaft of a vertical and rotary switch, for example. Such magnet which is subjected to momentary heavy loads of current must be provided with protecting means preventing it from burning out in case it should, through some fault, become permanently connected to the current source. There are, of course, supervisory signaling arrangements provided in an automatic exchange which call the attention of an office attendant to such emergency. However, the attendant might be otherwise occupied, or the switch may be located in a branch exchange not having an attendant at all. I have devised a magnet capable of withstanding heavy loads for an appreciable length of time without any detrimental results, and I have also improved the efficiency of the magnet by improving its magnetic properties.

The magnets usually employed for effecting the movements of a switch have two separate solid cores each provided with a winding and mounted on a common heel piece. In my improved magnet, I use only one laminated core for reducing eddy currents and thus preventing excessive heat production in case of a permanent connection. Incidental to combining two cores into one, the total air-gap required between the armature and the core in view of residual magnetic forces is reduced as far as the magnetic circuit is concerned by one-half of the air-gap resulting for the magnetic flux if two cores are used.

To explain this point a little further, if two cores are used, a certain air-gap will be adjusted between the armature and the two cores, while the armature is in operated position. The magnetic circuit between the two cores will therefore be interrupted at two points, viz, the two air-gaps between each of the cores and the armature. Using only one core, it will be apparent that I am enabled 10 with my improved magnet, to retain the same air-gap as in the former case, and at the same time reduce the air-gap for the magnetic flux.

As will be seen from the detailed description, the magnet is also provided with an 15 adjustable heel piece, comprising two parts. One of these parts is provided with slots, the other with corresponding threaded holes. The two parts are rigidly held together by means of screws extending through the slots 20 on one part of the heel piece and taking hold in the threaded holes of the other part. The heel piece is adjusted with the magnet energized and the armature in attracted position. It will be evident that the movable part of 25 the heel piece will be attracted by the armature, thus closing a magnetic circuit next to perfect, in which position it will be secured by means of tightening the screws. Although the principal purpose of the adjustable heel 30 piece is to improve the magnetic properties of the magnet, there are other advantages accruing from this arrangement which will be brought out as the description progresses.

From the above somewhat cursory account 35 of the various objects, it will be apparent, that my invention presents several advantages. The novel method of advancing the line wipers out of engagement with the contacts in a level, reduces the mechanical friction to a minimum, eliminates undue wear of the various parts, increases the reliability of 40 operation, benefits the maintenance of the apparatus, and at the same time increases its efficiency and lowers the operating expenses. 45 The simplified bank contact arrangement and the simplified novel wipers I propose, tend to further lower the cost of the mechanism by cheapening the process of manufacture and contributing also toward the advantages 50 enumerated above. The objects and features discussed in connection with the novel magnet also contribute toward reliable operation and utmost efficiency, due to the improved magnetic properties.

55 I shall now enter a detailed description of the operations of my invention, which I have shown incorporated in a well known switching mechanism of the vertical and rotary type.

60 Referring now to the drawings forming a part of this specification—

Figs. 1 and 2 illustrate the usual and the 65 novel arrangement of bank contacts, respectively, indicating also the relation of the wipers during the rotary operation of the

switch, or rather to say, just before the rotary operation commences;

Fig. 3 is a front view of a switch mechanism, with the bank contacts but indicated and details not necessary for a clear understanding omitted. The switch is shown in normal or non-operated position;

Fig. 4 illustrates the position of the line wipers in normal position, as seen from lines B—B in Fig. 3;

Fig. 5 is a side view of the switch illustrated in Fig. 3, shewing also a cross section of the bank contacts;

Fig. 6 illustrates the position of the line wipers in operated position as seen from lines A—A, Fig. 5;

Fig. 7 shows a circuit diagram for use with the switch mechanism disclosed in Figs. 3 and 5;

Figs. 8 and 9 illustrate a preferred form 85 of carrying out my invention; Fig. 8 showing the relation of the various parts just before the rotary movement of the switch commences, while Fig. 9 shows the switch in talking position, the line wipers being in engagement with their contacts, and the tension of the private wiper being increased;

Fig. 10 shows the line wipers used with the switch seen in Figs. 8 and 9 as shown from lines C—C indicated in Fig. 9.

Fig. 11 shows a circuit diagram for use with a switch illustrated in Figs. 8 and 9; and

Figs. 12—15, inclusive, illustrate various 100 views of the novel operating magnet.

Referring now particularly to Fig. 1, I have shown schematically the usual arrangement of bank contacts. The upper row designated through the numeral 10, contains ten single contacts and represents the private 105 contacts in a certain level, while the lower row, designated 20, contains twenty contacts, arranged in pairs and separated by a partition 19, represents the corresponding line contacts. The first set of contacts 11, 12, and 110 13 belong, accordingly, to the first line or trunk in a certain level. The wipers 14, 15, and 16 are shown positioned opposite the level just before the rotary movement commences. It will be obvious that the line contacts located in the upper part of row 20, contact 12 being one of them, are exposed and will readily collect dust, while the contacts located underneath the partition 19, including contact 13, are protected from excessive dust collection. 115 Accordingly, wiper 15 and the line contacts of the upper row are more subjected to wear than the line contacts of the lower row with all the detrimental results discussed in a previous paragraph.

120 In Fig. 2, I have shown a novel arrangement of the contacts in a level, the line contacts being arranged in a similar manner as the private contacts. Like parts are designated alike and will be readily recognized with- 130

out elaborate explanation. It will be seen that the line contacts in row 20 are arranged in sequence and not in pairs as usual thus obviating a partition such as 19 in Fig. 1. 5 The wipers being of a novel construction which will be described later and which is best seen in Figs. 4 and 6, are shown in a position ready for commencing with the rotary movement. The private wiper 14 will, therefore, 10 by, brush with slight pressure over the contacts preceding the idle set, in case of a selector having an automatic rotary hunting movement, or preceding the private contact of a wanted line in case of a connector in 15 which the wipers are positioned upon the contacts by a directively controlled rotary movement, while the line wipers 15 and 16 are withdrawn from the contacts during rotation and brought into engagement with the proper set 20 only after they have been positioned, i. e., after the rotary movement is completed.

Summarizing the advantages of the arrangement shown in Fig. 2 over the one shown in Fig. 1, it will be evident that elimination 25 of the partition together with arranging the contacts in sequence will cheapen the process of production and obviate provisions for the prevention of inductive influence between two contacts; the lower side of the contacts being 30 protected from dust collection insures safe operation and simplifies maintenance, and unequal wear of the contacts and wipers is eliminated.

Proceeding with the description, I shall 35 now explain the operations of the improved switch mechanism illustrated in Figs. 3 and 5, having a bank contact arrangement such as described above and shown in Fig. 2.

The vertical and rotary operations of the 40 switch, shown in Figs. 3 and 5, or rather to say the manner of lifting the shaft in a vertical direction and rotating it in a horizontal plane, do not differ from the operations of the usual switch of the vertical and rotary type. I 45 shall, accordingly, not describe these well known operations, but only the modifications and improvements constituting my invention.

The switch consists of the usual apparatus 50 including the movable shaft indicated by the numeral 1. At its lower end, the shaft carries a private wiper 2 rigidly secured to the shaft by means of clamp 3, and two line wipers, designated 4 and 5, which are, by 55 means of an arrangement to be presently described in detail, secured to the shaft in a manner adapting them to follow the vertical and rotary movements of the shaft, and to be moved in a vertical upward direction longitudinally to the shaft, independently and in addition to the vertical motion of the latter, and out of their position in which they are held by spring 7. This latter, additional movement of the line wipers takes place after 60 the cessation of the rotary motion, and is ef-

fected by the armature 8 of a magnet 9, operating a rod 10, mounted on the switch frame at points 29 and 30 and having a number of projections, such as 11 at its lower end, not unlike the teeth of a comb. These projections 70 correspond to the various levels. The upper part 12 of the U shaped wiper carrier 13 will, during the rotary movement, slide in between a certain one of the projections in accordance with the level to which the shaft was 75 raised. Upon the operation of the magnet 9, the wiper carrier 13 will be moved upward and the wipers 4-5 will be brought into firm engagement with the proper line contacts, where they remain throughout the conversation, and will be withdrawn again by magnet 9 deenergizing upon the restoration of the switch shaft to normal position. 80

Referring now particularly to the method of mounting the line wipers, it will be seen from Figs. 3, 4, 5, and 6, Figs. 4 and 6 showing the position of the wipers relative to the contacts and to the rod 10, in normal and in operated position, respectively, as seen from lines A-A on Fig. 5 and B-B on Fig. 3, that the wipers 4 and 5 are insulated from each other and also from the carrier 13, by insulators indicated at 14-15 and 16-17, and mounted upon the lower portion 18 of the carrier 13. The shaft extends through both the lower and the upper portion of the U shaped carrier 13 at points 19 and 20. A clamp 21 having a projection 22, is fastened to the shaft by means of a screw 23. Projection 22 has riveted to it a pin 24, which extends through an opening 25 in the upper part 12 of the U shaped carrier 13. A coiled spring 7 inserted between clamp 14 and the lower part 18 of the carrier 13, keeps the latter in normal position with the upper part 12 closely attached to the projection 22 of clamp 21. 90

Considering Fig. 4 which shows the normal position of the wipers 4 and 5 relative to rod 10 and to the bank contacts, and recalling the vertical operations of the switch lifting the shaft up to a desired row or level which operation must be visualized in looking at Fig. 4, as taking place vertically towards the observer, it will be seen that the position of the wipers with regard to rod 10 and to the contacts will not be changed during the vertical movement of the switch. The upper part 12, of the carrier 13, however, will with each step, be positioned opposite a successive notch of the comb like lower structure of rod 10, each notch corresponding to a certain vertical step, or level. The wipers being rigidly secured to the lower part 18 of the carrier 13, will thus be raised step by step until they are positioned opposite the desired row. Upon the shaft rotating in, the pin 24 mounted upon the projection 22 of clamp 21, which is hinged to the upper part 12 of the carrier, will cause the latter 105 110 115 120 125 130

to follow the step-by-step rotary movement of the shaft, thereby advancing the wipers horizontally toward the proper set of contacts in a certain level.

5 It will be remembered from the description of Fig. 2 that the private wiper advances during the rotary movement slightly pressing against the contacts, while the line wipers are withdrawn from engagement with the 10 line contacts. It is obvious that the proper relation can easily be adjusted by means of clamps 3 and 21, respectively. Upon the cessation of the rotary movement, i. e., upon the private wiper reaching an idle line in case 15 of the selector, for example, the line wipers will have been positioned underneath and opposite the line contacts corresponding to the private contact, but will not be in engagement with them. Magnet 9 energizes at 20 this instant, attracting its armature 8, which normally rests against a stop 26. Armature 8, which has a projecting lever 27 extending into a groove provided on rod 10 at point 28, will now lift the rod 10 vertically upward, 25 thereby also lifting the wiper carrier 13, because of the upper portion 12 of the carrier being in engagement with one of the notches provided at the lower end of rod 10 as has been described.

30 The line wipers 4 and 5 mounted on the carrier, will in this manner be pressed firmly against the proper contacts only after the rotary movement has been completed, and they will be removed again shortly before the 35 release of the switches which takes place as usual. Thus the line wipers are in engagement with the line contacts solely when needed for talking or signaling purposes, as the case may be, but withdrawn during the 40 setting operation of the switch.

A preferred manner of carrying out my invention is shown in Figs. 8 and 9. The novel features of this modified arrangement, which will be detailed presently, reside in the manner of bringing the line wipers into engagement with the line contacts after they have been positioned by the rotary movement of the switch. In the former case this was effected by means of an additional magnet 45 operating upon the termination of the rotary motion, in the present case, the usual vertical magnet will be energized for this purpose, raising the shaft by one additional step thus forcing the line wipers into engagement with 50 the line contacts, and at the same time increasing the tension of the private wiper. In releasing, the line wipers will first be withdrawn from the line contacts, and the tension of the private wiper will be lowered before 55 the return-to-normal movement is effected.

The bank contact arrangement shown in Fig. 2 is also employed in this switch, and the mechanical construction of the private wiper is identical to that used with the switch 60 previously described, i. e., the private wiper

consists of a single arm designated through the numeral 1 normally resting against a back stop 2, and rigidly secured to the clamp 4 by means of a nut 5, the clamp 4 being fastened to the switch shaft 3 by a screw 6. 70

The line wipers are of a somewhat simpler construction than the line wipers previously shown. They will be described now in detail, reference being made to Figs. 8, 9, and 10, respectively. It will be seen from these figures 75 that the line wipers 7 and 8 are normally resting against back stops 9 and 10, and held together by means of the two mounting plates 11 and 12, but insulated from the mounting plates, and from each other, by insulators 80 13-14. A clamp 15, extending through the mounting plates, is fastened to the wiper assembly and the entire unit is rigidly secured to the switch shaft 3 by a screw 17, attached to the clamp 15. 85

It will be obvious that both the private wiper and the line wipers can readily be adjusted in their relative positions on the shaft with regard to the bank contacts, by simply regulating their positions by means of the clamps 4 and 15, respectively. The adjustment of the wipers will be in conformance to the positions shown in Fig. 8, viz, the private wiper 1 will be adjusted to exercise a slight pressure upon the private contacts during the 90 rotary movement of the switch shaft, while the line wipers 7 and 8 will be withdrawn from the line contacts and advanced between two adjacent rows or levels, underneath the row to which they were raised during the vertical movement. At the termination of the 100 rotary motion, the vertical magnet will receive a current impulse and lift the shaft by an additional step, thus completing the connection. During conversation the shaft will be mechanically locked in operated position. 105

The mechanism for accomplishing these operations is shown in Figs. 8 and 9. Fig. 8 illustrates the positions of the various parts after the shaft is raised and just before the 110 rotary movement commences, and Fig. 9 shows their position after the cessation of the rotary step-by-step motion, viz, upon the apparatus having seized a desired line or trunk. 115

Pointing out the differences in mechanical construction between the usual switch and the present one, it will be seen that dog 18 is pivoted at point 19 upon an angular holder 20, mounted on the switch frame by means of screws 21 and 33. Coiled spring 22 is fastened to the lower part 23 of the holder 20 and to the dog 18 at point 24, and holds the dog 18 in a normal position resting against stop 25 mounted on the switch frame. Dog 120 18 is located in the usual switch in the same position relative to the shaft, but is stationary. The purpose of this dog is to guide the switch shaft in its vertical motion, the dog 125 extending into a groove 26 upon the upper 130

part 27 of the shaft, as is shown in the projection above Fig. 8. During the rotary motion the switch shaft will rest on the dog 18 and also on dog 28 as can also be seen from the projection above Fig. 9, dog 28 being located opposite the guide dog 18 and longitudinally displaced by one vertical step, while the rotary dog 29, pivoted, together with 28 on a common pin 30 which is fastened to the switch frame by means of a clamp 31, will take hold in the teeth of the rotary ratchet cylinder 32 and prevent the shaft from rotating back under the tension of the usual restoring spring mounted in a housing 10 on top of the switch shaft.

Comparing this arrangement with the mechanical details of the usual switch it will be seen that I have merely separated the so called double dog into two parts, 28 and 29, 20 assigning each part a separate function as will be seen later on, and that I employ a movable guide dog 18, which in the usual switch is stationary.

Continuing the description with reference to Fig. 9. The rotary movement will be terminated upon the private wiper 1 reaching an idle trunk in case of a selector having an automatic horizontal hunting motion or upon being advanced to a wanted line in case 30 of a connector. The vertical magnet of the switch will now receive an additional current impulse in a manner to be described later and lift the shaft one additional step. In the usual switch, no additional vertical step could be effected because of the vertical guide dog being stationary. In the present mechanism, however, having a movable guide dog 18, the switch shaft will respond to the additional energization of the vertical magnet 35 and line wipers 7 and 8 will be forced into firm engagement with the line contacts as shown in the drawing Fig. 9, while the tension of the private wiper 1 will be increased. Dog 28 will thereby take hold in a successive tooth of the vertical ratchet part 27 of shaft 40 3 thus locking the shaft mechanically in operated position, while the guide dog 18 will be lifted up on the incline of the obliquely shaped tooth to which it was previously engaged, but will be prevented from engaging 45 the next tooth in succession, because of the surface displacement between the tooth and the front or gripping part of the dog. In other words the shaft, which was supported 50 by both dogs 18 and 28, during the rotating movement, will now be supported by dog 28 only, and the guide dog 18 will merely rest upon the vertical tooth corresponding to the 55 engaged level, as can easily be seen from the drawing.

Upon terminating the call, the subscribers will hang up their receivers and cause the restoration of the switch to normal position. The release magnet will energize and attract 60 its armature indicated at 34. The adjustable

pin 35 attached to the armature of the release magnet will thereby strike against the projecting arm 36 of the upper dog 28, causing it to withdraw from the respective vertical tooth, and allowing the shaft to release vertically by one step. Guide dog 18 takes hold again in the corresponding tooth of the vertical ratchet part 27 and the line wipers 7 and 8 assume their normal position between the levels, while the tension of the private wiper 1 is reduced to normal. As is clearly indicated on the drawing, the arm 36 of dog 28 extends downward overlapping lever 37 which is a projection of the rotary dog 29. Arm 36 continuing its restoring motion, will accordingly, strike lever 37, which causes the rotary dog 29 to withdraw from engagement with the rotary ratchet cylinder 32. The tension of the restoring spring will be effective now and restore the switch to normal as usual, except that the line wipers are withdrawn from engagement with the line contacts.

In Figs. 7 and 11, I have shown, by means of conventional diagrams, circuits to be used for operating the switch mechanisms illustrated in Figs. 3-5 and 8-9, respectively. As these two circuits are practically identical, I shall furnish but one description and shall point out the differences in operation wherever they occur. It should be borne in mind that the differences will appear upon the switches seizing an idle trunk, as it is assumed that the switches shown are selectors having an automatic hunting movement. In case of the circuit shown in Fig. 7, which is intended for operating the switch mechanism shown in Figs. 3 and 5, the additional magnet designated through the numeral 90 will be operated upon the energization of the switching relay 50, while in the circuit shown in Fig. 11, which is assumed to operate with the apparatus illustrated in Figs. 8 and 9, the vertical magnet 60 will receive an additional impulse.

Referring now to Figs. 7 and 11, respectively, when such selector is seized (by a line switch or by another selector, as the case may be), the line relay 10, which is connected to the line conductors 7 and 8 through contacts on the switching relay 50 energizes and closes a circuit for the release relay 20 from ground through the armature 54 of the switching relay 50. The release relay 20 energizes and places ground on the release trunk conductor 9 by means of its armature 21 to maintain the preceding switch operated and to provide a subsequently closed circuit for the switching relay 50, which is now prepared through the stepping relay 40, by way of interrupter contacts 71 of the rotary magnet 70 and off normal contacts 5, the latter being open at this instant. The release relay 20 also opens a point in the circuit of the release magnet 80 and at the same time prepares a circuit for the vertical magnet 60 at its armature 22.

When the calling subscriber dials the next digit in the desired number—(the first digit in the case of a first selector)—the line relay 10 deenergizes a number of times corresponding to the digit for which the dial was operated. Upon each deenergization, the line relay 10 opens at its armature 11, the circuit of the release relay 20, but this relay is slow acting and maintains its armatures attracted throughout the series of deenergization. As a further result of each deenergization, the line relay closes a circuit for the vertical magnet 60 through the armature 22 and its working contact by way of the series relay 30. The vertical magnet operates responsive to the current impulses delivered in this manner, and raises the wipers of the switch step by step until they are positioned opposite the desired level of bank contacts. The slow acting series relay 30 energizes in series with the vertical magnet 60 upon the first impulse delivered to the latter and it energizes before the shaft is operated through the first step. This is not due to any special adjustment, but merely due to the fact that a relay of the type used in this case operates more quickly than the vertical magnet can possibly pull up and lift the shaft. Upon energizing, the series relay 30 opens a point in the operating circuit of the rotary magnet 70 and places a short circuit around the switching relay 50 by means of its armature 31. The short-circuiting of the switching relay 50 serves to prevent its premature energization and also to prepare a direct current circuit for the stepping relay 40 which is closed as soon as the switch completes its first vertical step, this latter circuit includes the interrupter contacts 71 controlled by the rotary magnet. Accordingly, the stepping relay 40 energizes as soon as the off normal springs 5 close and at armature 41 closes a locking circuit for itself to ground. At its lower armature 42, the stepping relay prepares a circuit for the rotary magnet 70 which, however, is not completed at this time on account of the fact that the slow acting series relay 30 is maintained operated throughout the vertical movement.

Shortly after the termination of the series of impulses delivered to the vertical magnet, the slow acting series relay 30 deenergizes and opens the original circuit of the stepping relay 40. This latter relay, however, remains locked up and the switching relay 50 remains short circuited to ground at the upper armature 41 of the stepping relay. As a further result of the deenergization of the series relay 30 a circuit is completed for the rotary magnet 70 from ground at armature 21 by way of armatures 31 and 42. The rotary magnet 70 energizes and advances the wipers into engagement with the first set of bank contacts in the level opposite which they were previously raised. Near the end of its stroke, the rotary

magnet opens at its interrupter contacts 71, the circuit of the stepping relay 40. Responsive to this stepping relay deenergizes and opens at its armature 24 the circuit of the rotary magnet 70, whereupon the rotary magnet 70 deenergizes also, again closing its interrupter contacts 71.

From this point the further operations depend upon whether the trunk terminating in the first set of bank contacts is busy or idle. If it is idle, the switching relay 50 energizes now, owing to the fact that the short circuit is removed from around its winding at the upper armature 41 of the stepping relay 40. Assuming, however, that the trunk is busy, the switching relay 50 is still short circuited because there is a ground potential encountered at the test contact of the busy trunk by the test wiper 2, and therefore the switching relay cannot energize. In this case the stepping relay operates again, this time to ground at the test contact of the busy trunk by way of the test wiper 2, and again closes its locking circuit and the circuit of the rotary magnet whereupon the latter operates again and advances the wipers into engagement with the next set of bank contacts.

This alternate operation continues until an idle trunk is reached, which trunk, it may be assumed, is the one shown in the drawings. When this idle trunk is reached, the switching relay 50 being no longer short circuited energizes in series with the stepping relay 40. The stepping relay, however, cannot operatively energize at this time on account of the high resistance of the switching relay. Upon energizing, the switching relay 50 removes ground, at its armature 54, from the armature 11 of the line relay, thereby opening the circuit of the slow acting release relay 20; disconnects the test wiper from the junction of its own winding and the winding of the stepping relay 40, at its armature 52 and connects it instead to the grounded release trunk conductor, thereby also extending ground to the release trunk conductor of the seized switch and making it busy immediately; and at its upper and lower armatures 51 and 55 disconnects the incoming trunk conductors 7 and 8 from the upper and lower windings of the line relay 10. The further operations of the two switches are somewhat different and will be described separately.

The operations of the circuit, Fig. 7, which is designed to operate with the switching mechanism shown in Figs. 3 and 5, shall be explained first. It will be remembered that said switching mechanism is provided with an additional magnet designated through the numeral 9, which magnet must operate whenever an idle trunk is tested free, for the purpose of operating the rod 10, which moves the wiper carrier 13, and with it the line wipers 4 and 5 into engagement with the line contacts. This magnet is shown in the circuit,

Fig. 7 and indicated through the numeral 90. The switching relay 50 in addition to its various functions, explained above, also attracts its armature 53 and closes thereby a circuit for magnet 90. Wipers 1 and 3 will be forced up and against the line contacts corresponding to the private contact engaged by the test wiper 2 thereby extending the incoming line conductors to the corresponding conductors of the seized trunk line.

Referring to Fig. 11, which operates in connection with the switch shown in Figs. 8 and 9. The switching relay 50 upon energizing, closes also its armature 56. The slow acting release relay 20 whose circuit is opened at the same time at armature 54 of the switching relay, will not fall back immediately due to its slow action, and keeps its various armatures closed for an appreciable period. A circuit will therefore result for the vertical magnet 60 from ground at armature 56 of the switching relay by way of armature 23 of the slow acting release relay. The vertical magnet operates and causes the line wipers 1 and 3 to engage the corresponding line contacts of the seized trunk, whereupon they will be locked mechanically as described.

The further operations of the switches taking place in extending a call are identical again and shall be described together. The line and release relays of the switch on the seized trunk line—(selector, connector or repeater, as the case may be)—energize now and the latter places ground on the associated release trunk conductor, which ground is extended back through the private wiper of the selector in question and armature 52 of the switching relay 50 to the release trunk conductor 9 before the slow acting release relay 20 has had time to deenergize and to remove local ground from the release trunk at its armature 21. This, of course, is the usual holding circuit which is established when one automatic switch seizes another and cuts through. The calling subscriber now proceeds to dial the remaining digits in the desired number, thereby setting up the connection through a connector switch or through another selector and a connector switch, as the case may be. In any event the selectors shown perform no other operation until the calling party replaces the receiver.

When the receiver is replaced at the calling substation, the ground potential is removed from the release trunk by the connector switch in use—(or by a repeater or similar circuit in other cases)—whereupon the switching relay 50 deenergizes. The release operations of the two switches differ slightly and I shall therefore consider them separately.

In the selector, Fig. 7, the switching relay 50 upon deenergizing, opens its armature 53, and disconnects thereby the additional magnet 90, which causes the line wipers 1 and 3 to

withdraw from the line contacts in the bank and to assume their normal position between two adjacent levels as described. At armature 54, the switching relay 50 closes a circuit for the release magnet 80 by way of armature 11 of the line relay, armature 22 of the release relay and off normal springs 6. The release magnet 80 energizes now and restores the switch to its normal position as usual.

It should be observed that the opening of the armature 53 which causes the restoration of magnet 90 and the consequent withdrawal of the line wipers from the associated contacts, and the closing of armature 54 resulting in the energization of the release magnet, occur almost simultaneously. Although there will be a difference in time between the deenergization of the magnet 90 and the effective operation of the release magnet 80 due to the relative inertia of the parts operated by the two magnets, i. e., the magnet 90 will deenergize and cause the removal of the line wipers from the line contacts before the energization of the release magnet can possibly actuate the release mechanism, it will be evident that an adjustment between the two armatures 53 and 54, causing the first to open before the latter closes can easily be effected and will preclude any possibility of trouble. In other words, the adjustment of the mechanism must be such that the line wipers are withdrawn from the line contacts before the return to normal movement commences. No difficulties will be experienced in bringing about the proper functions, simply due to the difference in mechanical inertia of the various moving parts, as I have intimated above, as it is obvious that the moment of inertia of the wiper carrier is less than that of the entire shaft including the wipers. The wipers will therefore follow the operation of the magnet 90 quicker than the shaft can follow the energization of the release magnet. The adjustment of the two contacts will therefore be more of a character of additional precaution.

In the switch illustrated in Fig. 11, switching relay 50 upon deenergizing closes armature 54 and completes thereby the circuit for the release magnet 80. The withdrawal of the line wipers from the line contacts and the lowering of the tension of the private wiper takes place as described, and the switch is then restored to normal position as usual. The circuit of the release magnet is opened at the associated off normal springs 6 as soon as the shaft assumes its normal position.

The selector is now at normal and in readiness to be used in completing a subsequent connection.

In Figs. 12-15, inclusive, I have shown a new type of operating magnet. As will be remembered from the brief account given previously, the novelty resides in the arrangement of the adjustable heel piece and in using

one laminated core in place of two separate solid cores. The manifestation of eddy currents is thereby reduced to a minimum, preventing destruction of the magnet if connected to current for an undue period of time, and its magnetic qualities are considerably improved. The magnet may be used in place of the vertical, rotary or release magnet in the usual or improved type of vertical and rotary switch mechanism shown and described in the present case.

Referring now to the drawings, Fig. 12 is a side, and Fig. 13 a back view, showing the magnet in operated position with the armature attracted; Fig. 14 illustrates the magnet in normal or nonoperated position, and Fig. 15 is a sectional view. It will be seen that the heel piece consists of two parts designated through the numerals 1 and 2, respectively, and held together by means of screws 3 and 4. The lower heel piece is provided with longitudinal slots 5 and 6, for the purpose of allowing convenient adjustment of the upper part of the heel piece. The laminated core 7 is riveted at the lower end to a mounting plate 8, which is rigidly secured to the lower angular part of the heel piece by means of counter sunk screws, as is indicated at 9. The core 7 serves as a center for the winding 30 of coil 10 which is protected at its upper and lower end by the usual insulators 11 and 12, and terminated by a heavy insulating plate 13. The magnet may be mounted in the usual manner on the switch frame or other parts, 35 depending upon the purpose it is intended to serve. The armature 14 is brought into relation with the magnet as shown in the drawings and is pivoted on pins 15 and 16, mounted on the switch frame at 17 and 18.

Referring now particularly to Fig. 14. After mounting the magnet in its proper place, the required air-gap will be adjusted by inserting the usual thickness gauge between armature and core and connecting the magnet to current. Accordingly, the magnet energizes and attracts its armature 14 and the movable part 2 of the heel piece pulls up also, the screws 3 and 4 not being tight at this moment. The heel piece attaches itself at its upper end to a point at the inner surface of the armature. The screws will be tight now securing the heel piece in its proper position. The magnet is now adjusted and ready for operation. In energizing the magnet will appear as shown in Figs. 12 and 13 with the heel piece closely engaging the armature.

The adjustable heel piece has several advantages. In the first place, adjustment is rendered extremely simple because any variations in the size of the core or armature will be taken up by the heel piece without any fitting, which is of particular advantage in case of readjustments; secondly, the mechanical parts are made easily accessible; and thirdly, the magnetic properties of the magnet are

considerably improved due to the closed magnetic circuit, rendered by the heel piece closely attaching to the armature. As an additional advantage, it may be understood that an accurate and uniform adjustment of a great number of magnets can be accomplished without necessitating accurate and uniform parts. The use of a single laminated core instead of double solid cores, renders the magnet self protecting, cheapens the process of manufacture and contributes also to improving the magnetic properties of the magnet.

It will be apparent from the foregoing description that I have devised several improvements applicable to switching mechanisms used in telephone signaling and allied systems, rendering the apparatus reliable in use, cheapening the process of production and answering all requirements set for safe and economical operation. I desire it to be understood that the manner of carrying out my invention as shown in the drawings is by way of example only and that I do not want to be limited in the application of the disclosure.

What I consider new shall be pointed out in the following claims.

What is claimed is:

1. An automatic switching mechanism having a vertically and horizontally movable shaft provided with a pair of wipers, terminals arranged in horizontal rows accessible to said wipers, means for advancing said wipers along said terminals but out of engagement therewith, to select certain of said terminals, and means for then moving said wipers in a direction longitudinally to said shaft to engage the selected terminals.

2. An automatic switching mechanism having a vertically and horizontally movable shaft provided with a pair of wipers, terminals arranged in horizontal rows accessible to said wipers, means for advancing said wipers along said terminals but out of engagement therewith, to select certain of said terminals, and means for then moving said wipers independently of but in a direction longitudinally to said shaft to engage the selected terminals.

3. An automatic switching mechanism having a vertically and horizontally movable shaft provided with a pair of wipers, terminals arranged in horizontal rows accessible to said wipers, means for advancing said wipers along said terminals but out of engagement therewith, to select certain of said terminals, and electromagnetic means operable upon certain of said terminals being selected, for moving said wipers independently of, but in a direction longitudinally to said shaft, to engage said selected terminals.

4. An automatic switching mechanism having a vertically and horizontally movable

shaft provided with a pair of wipers, terminals arranged in horizontal rows accessible to said wipers, means for advancing said wipers along said terminals but out of engagement therewith, to select certain of said terminals, and electromagnetic means operative upon and during the seizure of certain of said terminals for moving said wipers independently of but in a direction longitudinally to said shaft to engage the selected terminals.

5. An automatic switching mechanism having a vertically and horizontally movable shaft provided with a pair of wipers, terminals arranged in horizontal rows accessible to said wipers, means for advancing said wipers along said terminals but out of engagement therewith, to select certain of said terminals, and electromagnetic means effective upon certain of said terminals being selected for causing said wipers to engage said terminals, and for locking said wipers in operated position.

6. An automatic switching mechanism having a vertically and horizontally movable shaft provided with a pair of wipers, terminals arranged in horizontal rows accessible to said wipers, means for advancing said wipers along said terminals but out of engagement therewith, to select certain of said terminals, and electromagnetic means operative upon the seizure of certain of said terminals for moving said wipers in a vertical direction to cause said wipers to engage said terminals, and to lock said wipers in operated position.

7. An automatic progressively movable switch having a shaft provided with a pair of wipers, terminals arranged in groups in horizontal rows, a first electromagnetic means for moving said wipers in a vertical plane to select a group, a second electromagnetic means for moving said wipers in a horizontal plane underneath said terminals but out of engagement therewith, to select certain of said terminals, and a third electromagnetic means for then moving said wipers to engage the selected terminals.

8. An automatic progressively movable switch having a shaft provided with a pair of wipers, terminals arranged in groups in horizontal rows, a first electromagnetic means for moving said wipers in a vertical plane to select a group, a second electromagnetic means for moving said wipers in a horizontal plane underneath said terminals but out of engagement therewith, to select certain of said terminals, and a third electromagnetic means for then moving said wipers independently of said shaft to engage the selected terminals.

9. An automatic progressively movable switch having a shaft provided with a pair of wipers, terminals arranged in groups in horizontal rows, a first electromagnetic

means for moving said wipers in a vertical plane to select a group, a second electromagnetic means for moving said wipers in a horizontal plane underneath said terminals but out of engagement therewith, to select certain of said terminals, and a third electromagnetic means effectively operative upon and after the seizure of said terminals for moving said wipers into engagement therewith and for keeping said wipers in operated position.

10. An automatic progressively movable switch having a shaft provided with a pair of wipers, terminals arranged in groups in horizontal rows, a first electromagnetic means for moving said wipers in a vertical plane to select a group, a second electromagnetic means for moving said wipers in a horizontal plane underneath said terminals but out of engagement therewith, to select certain of said terminals, and means effective upon seizure of said terminals for moving said wipers to engage said terminals, and for locking said wipers in operated position.

11. An automatic progressively movable switch having a shaft provided with a pair of wipers, terminals arranged in groups in horizontal rows, a first electromagnetic means for moving said wipers in a vertical plane to select a group, a second electromagnetic means for moving said wipers in a horizontal plane underneath said terminals but out of engagement therewith, to select certain of said terminals, and means for moving said wipers into engagement with the selected terminals, and for locking said wipers in operated position.

12. An automatic progressively movable switch having a shaft provided with a pair of wipers, terminals arranged in groups in horizontal rows, a first electromagnetic means for moving said wipers in a vertical plane to select a group, a second electromagnetic means for moving said wipers in a horizontal plane underneath said terminals but out of engagement therewith, to select certain of said terminals, and means for moving said wipers to connect with the selected terminals and for withdrawing said wipers during the restoring operation of said switch.

13. An automatic progressively movable switch having a shaft provided with a pair of wipers, terminals arranged in groups in horizontal rows, a first electromagnetic means for moving said wipers in a vertical plane to select a group, a second electromagnetic means for moving said wipers in a horizontal plane underneath said terminals but out of engagement therewith, to select certain of said terminals, and separate means independent of said shaft and said electromagnetic means for causing said wipers to engage the selected terminals and for withdrawing said wipers during the restoring operation of said switch.

14. An automatic remotely controlled switching mechanism having a movable member provided with wipers, terminals associated with trunk lines provided for transmitting electric energy thereover, said terminals being arranged in physical sequence in rows, means for advancing said wipers parallel to and between two adjoining rows of terminals but out of engagement therewith, to select certain of said terminals, and means for then moving said wipers to engage the selected terminals.
15. An automatic remotely controlled switching mechanism having a movable member provided with wipers, terminals associated with trunk lines provided for transmitting electric energy thereover, said terminals being arranged in physical sequence in rows, means for advancing said wipers parallel to and between two adjoining rows of terminals but out of engagement therewith, to select certain of said terminals, and means for then moving said wipers independently of said movable member to engage the selected terminals.
16. An automatic remotely controlled switching mechanism having a movable member provided with wipers, terminals associated with trunk lines provided for transmitting electric energy thereover, said terminals being arranged in physical sequence in rows, means for advancing said wipers parallel to and between two adjoining rows of terminals but out of engagement therewith, to select certain of said terminals, and separate means for then moving said wipers independently of but longitudinally to said movable member to engage the selected terminals.
17. An automatic remotely controlled switching mechanism having a movable member provided with wipers, terminals associated with trunk lines provided for transmitting electric energy thereover, said terminals being arranged in physical sequence in rows, means for advancing said wipers parallel to and between two adjoining rows of terminals but out of engagement therewith, to select certain of said terminals, and means for moving said wipers to engage the selected terminals only when needed for transmitting current thereover.
18. An automatic remotely controlled switching mechanism having a movable member provided with wipers, terminals associated with trunk lines provided for transmitting electric energy thereover, said terminals being arranged in physical sequence in rows, means for advancing said wipers parallel to and between two adjoining rows of terminals but out of engagement therewith, to select certain of said terminals, and means for moving said wipers to engage the selected terminals only when needed for transmitting energy thereover, and withdrawing said wipers during the restoring operations of said switching mechanism.
19. An automatic remotely controlled switching mechanism having a movable member provided with wipers, terminals associated with trunk lines provided for transmitting electric energy thereover, said terminals being arranged in physical sequence in rows, means for advancing said wipers parallel to and between two adjoining rows of terminals but out of engagement therewith, to select certain of said terminals, and means for moving said wipers to engage the selected terminals only when needed for transmitting energy thereover, and for locking said wipers in operated position.
20. A switching device having a movable member provided with a plurality of wipers, terminals associated with trunk lines provided for transmitting electric energy thereover, said terminals being arranged in physical sequence in horizontal rows, directly controlled means for operating said movable member to select a row containing certain desired terminals, means for then operating said movable member to advance said wipers underneath the terminals in said row but out of engagement therewith, to select said desired terminals, and automatically operated means to move said wipers to connect with said selected terminals only when needed for transmitting energy thereover.
21. A remotely controlled switching device having a movable member, a plurality of brushes secured to said member, a plurality of terminals associated with trunk lines provided for transmitting electric energy thereover, said terminals being arranged in physical sequences in rows, means for operating said movable member to advance said brushes parallel to said terminals but out of engagement therewith to select certain of said terminals, and means for moving said brushes to engage the selected terminals only when needed for transmitting energy thereover.
22. A remotely controlled switching device having a movable member provided with a plurality of brushes, a plurality of terminals associated with trunk lines provided for transmitting electric energy thereover, said terminals being arranged in physical sequence in rows accessible to said brushes, means for operating said movable member to advance said brushes parallel to said terminals but out of engagement therewith to position said brushes opposite certain of said terminals, and means for then displacing said brushes relative to said movable member and in a direction longitudinal thereto to engage the selected terminals.
23. A switching mechanism having a movable shaft provided with one test and two line wipers, terminals associated with trunk lines arranged in groups in horizontal rows accessible to said wipers, one test terminal and two

- line terminals representing a trunk line, the test and the line terminals of a group being located in two separate rows in physical sequence, and means for advancing said wipers 5 over said terminals to select an idle trunk line.
24. A switching mechanism having a movable shaft provided with one test and two line wipers, test, and line terminals associated 10 with trunk lines arranged in groups in horizontal rows accessible to said wipers, the test and the line terminals of a group being located in two separate rows in physical sequence, each trunk having a test terminal in a 15 test row and two adjoining line terminals in the corresponding line row, and means for moving said wipers into engagement with a desired set of terminals.
25. A switching mechanism having a movable shaft, a pair of wipers mounted on a U-shaped carrier secured to said shaft and provided with a fan-like extension, a rod located in front of and longitudinally to said shaft and provided at its lower end with a plurality of projections, terminals arranged in groups in horizontal rows, means for moving said shaft axially to position said wipers 20 relative to a certain group of terminals, means for then moving said shaft radially 25 to advance the wipers towards certain terminals within said row but out of engagement therewith, while the fan-like extension of said carrier advances between two projections of said rod corresponding to the selected 30 group, and means for operating said rod to cause a displacement of said carrier in a direction longitudinal to said shaft to move said wipers into engagement with the selected 35 terminals.
- 40 26. A switching mechanism having a movable shaft, a U-shaped member carrying at one end a pair of wipers, and provided at its other end with a fan-like segment, means for fastening said member to said shaft, including a clamp provided with a projecting arm carrying a pin extending through said segment, said shaft extending through the legs of said member and through said clamp, a helically wound expansion spring inserted 45 between said clamp and one leg of said member, terminals arranged in groups in horizontal rows, a longitudinally movable rod provided with a plurality of notches, each 50 notch corresponding to a certain row, means for moving said shaft longitudinally to position said wipers relative to a certain row of terminals and to position the segment relative to the corresponding notch provided on said rod, means for then moving said shaft 55 radially to advance said wipers towards certain terminals within said row but out of engagement therewith while said segment is being rotated within said notch, and means including an electromagnet for then moving 60 an angular lever extending into a groove 65 provided on said rod, for causing a longitudinal displacement of said member to move said wipers into engagement with the selected terminals.
27. A switching mechanism having a movable shaft carrying a member longitudinally movable relative to said shaft and provided with a pair of wipers at one end and a projecting guide segment at the other end, said wipers being radially displaced 70 by 180 degrees relative to said segment, terminals arranged in groups in horizontal rows, a movable rod located in front of and longitudinally to said shaft and provided with a plurality of guide notches, each notch 75 corresponding to a certain row, means for moving said shaft axially to position said wipers opposite a desired row and to position said guide segment opposite a guide notch corresponding to said row, means for 80 then moving said shaft radially to advance said wipers towards certain terminals within said row but out of engagement therewith and to advance said guide segment within 85 said guide notch, and means for moving said 90 rod to cause said wipers to engage the selected terminals.
28. An automatic switching mechanism, having a movable member provided with wipers, terminals being arranged in physical sequence in rows, means for advancing said wipers parallel to and between two adjoining rows of terminals but out of engagement therewith, to select certain of said terminals, and means for then moving said wipers to engage the selected terminals. 95
29. A two-directional step-by-step switch in which the wipers are adapted to be operated in three stages, first in one direction and then in second direction and finally in 100 a direction parallel to the first direction. 105
30. A two-directional automatic switch comprising a shaft carrying wipers adapted to move axially and to rotate to engage terminals arranged in horizontal rows in which the wipers are rotated parallel to said terminals but out of engagement therewith to select a particular set of terminals and then in a direction parallel to the axis of said shaft to engage a particular set of terminals. 110
31. A step-by-step automatic switch in which a plurality of sets of terminals are arranged in rows with the terminals of a set adjacent to each other and in which the switch wipers are advanced parallel to and between two rows but out of engagement with said terminals of a selected set and finally moved in a plane to establish connection with the terminals of the selected set. 115
32. A step-by-step automatic switch having wipers and a plurality of sets of terminals arranged in rows with the terminals of a set adjacent to each other, means for moving the wipers of the switch in one direction opposite to a particular set of terminals, 120 125

means for moving said wipers in another direction beneath but out of engagement therewith, and means for causing said wipers to engage the selected set of terminals.

5. 33. An automatic switch provided with wipers, a plurality of rows of spaced terminals, means for moving said wipers in one direction to any space between said rows of terminals, means for moving said wipers in

another direction in the selected space but out of engagement with the terminals, and means for causing the wipers to again move in the first direction to engage said terminals.

In witness whereof, I hereunto subscribe my name this 9th day of September, A. D., 1925.

JOHN ERICKSON.
